[57] CLAIM

The ornamental design for a folding balcony table, as shown and described.

DESCRIPTION

FIG. 1 is a top, front, and right side perspective view of a folding balcony table showing my new design, the fragmentary, broken-line depiction of a balcony being for illustrative purposes only and forming no part of the claimed design;

FIG. 2 is a top plan view thereof;

FIG. 3 is a front elevational view thereof;

FIG. 4 is a right side elevational view thereof, the left side being a mirror image of that shown;

FIG. 5 is a right side elevational view thereof, with the table shown in a collapsed position;

FIG. 6 is a top, front, and right side perspective view thereof, with the table shown in a collapsed position; and

FIG. 7 is a top, front, and right side perspective view of an alternative embodiment thereof, the only difference residing in the substitution of a transparent for an opaque top.

FIG. 1**FIG. 2****FIG. 3****FIG. 4**

FIG. 5**FIG. 6****FIG. 7**
